UNITED STATES PATENT OFFICE

159,157

BOX

Gerald F. Koester, Bronx, N. Y.

Application April 15, 1947, Serial No. 138,406

Term of patent 14 years

(Cl. D58—12.6)

To all whom it may concern:

Be it known that I, Gerald F. Koester, a citizen of the United States of America, residing in the county of Bronx, State of New York, have invented a new, original, and ornamental Design for a Box, of which the following is a specification, reference being had to the accompanying drawing forming part thereof, wherein:

Figure 1 is a top plan view of a box, showing my new design,

Figure 2 is a front elevation thereof,

Figure 3 is a side elevation thereof,

Figure 4 is an exploded perspective view of the box showing the cover raised to expose the interior.

Figure 5 is a cross sectional view taken on line 5—5 of Figure 1.

I claim:

The ornamental design for a box, as shown.
GERALD F. KOESTER.
